SHEET FEEDING AND EJECTING MEANS

Amos Calleson and Edgar A. Calleson,
Merrick, N. Y.

Application October 31, 1934, Serial No. 750,788

19 Claims. (Cl. 271—32)

This invention relates to mechanism for feeding sheets one after another from a stack of superposed sheets, for instance, as where the feeding takes place past a coactive punch and die to operate on the sheets.

In general, the objects are to effect the separation of the sheets always one by one from the stack and to provide an improved and novel means for causing ejection of each sheet at the end of the feeding operation. More particularly, the objects are to have the feeding and ejecting operations entirely automatic, so that the attendant's duties are confined to supplying the machine with a fresh stack as the previous stack becomes exhausted and removing the product resulting from the punching operation.

In the drawings,

Fig. 1 is a left side and Fig. 2 a front elevation of the machine;

Fig. 3 is a fragmentary view of rack 8 and its actuating means, the latter appearing in front elevation and parts appearing in section in planes perpendicular to a shaft 13;

Fig. 4 is a section in a plane coincident with 25 and lengthwise of said shaft;

Figs. 5 and 6, continuations of each other, show the left- and right-hand end portions, respectively, of the table, rack, and means whereby the lowest sheet in the stack is, alone, made subject to advance by the rack, the view being in plan as seen by the attendant standing in working position (right of Fig. 1) and, leaning over, looking in the direction of the arrow in Fig. 1;

Figs. 6a to 6c appertain to mechanism in Fig. 35 6, Fig. 6a being a front and Fig. 6b a right side elevation of parts 22 and 22x; and Fig. 6c showing how the lowest sheet is separated from the next lowest sheet.

Fig. 7 is a section through Fig. 5 in a plane 40 through and lengthwise of a certain telescopic shaft;

Figs. 7a to 7f appertain to mechanism in Fig. 7, Figs. 7a and 7b being a plan and right end view of housing 27; Fig. 7c a front elevation of 45 a suction pump attached to the housing and a suction relief lever 53; Fig. 7d a right side elevation of abutment 23 and denter lever 11 and show the sheet in flat and also bent-down form; Fig. 7e a front elevation of bracket 46; and Fig. 50 7f showing the gripper detached;

Figs. 8 and 9 are, respectively, sections on lines 8—8 and 9—9, Fig. 6;

Fig. 10 is a section on line 10—10, Fig. 11, of 55 the sheet-ejecting mechanism;

Fig. 11 is a section on line 11—11, Fig. 10, being a continuation of Fig. 8;

Fig. 12 is a plan of said sheet-ejecting mechanism;

Fig. 13 is a front elevation, partly in section,

of the controlling means for the sheet-ejecting mechanism; and

Fig. 14 is a plan, partly in section, of a part of the mechanism appearing in Fig. 9.

The fixed structure or frame of the machine 5 includes the rigidly connected standards 1 and the downwardly inclined and laterally projecting bed 2 having a back wall 2a (Fig. 9) and forward thereof level 3a of two levels 3 and 3a separated by a transverse wall 39 (Fig. 8), level 3 10 being adapted to receive the die x (shown partially and dotted in Figs. 8 and 11) and level 3a 15 reaching laterally to a housing 27, the depressions at such levels being covered by plates y and z—z', (Figs. 2 and 3) the bed and such plates 20 flanking at the back by the plate 5 on back wall 2a. 4 designates the plunger carrying a punch 25 (not shown) to coact with the die when the plunger is reciprocated through a link 6 engaged with an eccentric portion of the main rotary shaft 7, as usual. The rack 8 is reciprocated in a guideway 9 from an eccentric stud 10 on a disk 11 affixed to shaft 7 as follows: A toothed segment 12, affixed to a rock-shaft 13 journaled in a bracket 14 depending from the table, meshes with the rack, the rock-shaft having an arm 15 30 to which is universally connected a link 16 also pivoted to stud 10, which may be adjusted by a screw 17 to alter the throw of the segment and hence of the rack. So much is substantially the known construction, and is not claimed 35 per se. The rack has a series of blocks 18 each having a tooth 18a overhung toward the die (but its top not above the top surface of the table) and arranged to move in a slot 9a between plates z and 5, the rack having a T-groove 8a 40 receiving blocks 19 whereby, through the medium of screws 19a, blocks 18 may be clamped to the rack in any predetermined spacing. The part of the sheet a' (Fig. 7) to be advanced which is over slot 9a is to be bent down into the path of 45 the rack teeth. When the stroke-length of the rack is altered, by adjusting stud 10 as described, the spacing of the toothed blocks 18 may be adjusted to agree.

Back of the slot 9a there is affixed to the table 50 a back-stop 20 for the stack a of sheets, the inclination of the table causing the stack to rest by gravity against such back-stop which is to form, with the table and right and left abutments to be referred to, a sheet magazine. The back-stop is secured by bolts 20a to the table 55 penetrating transverse slots in the back stop, permitting the latter's adjustment to suit various widths of sheets. A bracket 21 (Figs. 6, 8 and 9) upstands from and is bolted to the table and 60 traverses the slot 9a, being in effect arched or

cut away underneath, as at 21a, Fig. 9, so that the lowest sheet in the stack may pass under it toward the die. Affixed thereto is a plate 22 (Fig. 6a—6b) forming the right hand abutment and 5 having its lower edge portion 22a bent off toward the stack and formed with a chisel edge whose inclined face is underneath. Said edge portion forms what we term a separator for the sheets, the stack of sheets *a* being adapted to rest at its 10 right hand forward corner on this separator; said edge portion is spaced somewhat from the surface of plate *z* (Fig. 6c) so that when the lowest sheet has been retracted to the left it can pass to the right under said edge portion. 15 The left-hand abutment (Figs. 5, 7d and 7) is a plate 23 which is secured, Fig. 7e to an arm 46b of a bracket 46 (to be referred to) forward of the slot 9a and it has a lug 23a depending into a housing 27 (also to be referred to). The plates 20 22 and 23 respectively have blocks 22x (Fig. 6b) and 23x (Fig. 7d) secured thereto and forming forward abutments for the stack.

The left hand forward corner of the lowest sheet *a'* is to be pulled down clear of the lug 25 23a (Figs. 7d and 7) and then gripped and the sheet, alone, retracted clear of the separator 22a, whereupon the left hand extremity of the sheet is to be dented into the path of reciprocation of the extreme left-hand rack-tooth 18a, which will 30 then effect its first increment of advance toward the die and the deflection by the separator, away from the next overlying sheet, of its leading or right-hand end. For proper support of the lowest sheet at this time supporting structure 35 may be said to be formed by the table, on which the stack rests with its left side inclusive of its forward left corner projecting further than the table, and the rack 8 acting in part as a support for the projecting portion of the stack and arranged to be remote from said corner when the stack is so positioned, abutment 23 being opposed to said side of the stack and having a depending stop, as 23a, relatively between said support and said corner of the stack and terminating below 40 the top surface of the lowest sheet.

For this purpose there is the following mechanism:

Journaled in bearings 24a (Figs. 6 and 8) of a support 24 bolted to the table is a hollow shaft 50 25 receiving and splined at 25a (Figs. 6 and 9) to a shaft 26 journaled at its left-hand end in bearings 27a of a housing or support 27 (Figs. 7 and 7a—7b). As will appear, shaft 25 is held against but shaft 26 is capable of lengthwise displacement, and they form what we shall herein-after term a telescopic shaft to indicate its extensible nature, meaning, however, that its parts are incapable of relative rotation. This telescopic shaft, which at its left-hand end causes 60 the mentioned manipulation of the left-hand end of the sheet, is driven at its right-hand end as will now appear:

A housing 28 (Figs. 2 and 14) is bolted at 65 to the under side of the table and in it are fixed two stub-shafts 30 and 30a on which are journaled sprocket-wheels 31 and 31a connected by an endless chain 32, sprocket wheel 31 having affixed thereto a pulley 33 which is connected by a belt 34 with a pulley 35 on the main shaft 7 and the other sprocket wheel 31a having affixed thereto a pinion 36 (see also Figs. 8 and 9) which meshes with a ring-pinion 37 revoluble around a disk 38 which is affixed to the tubular element of the telescopic shaft (such element being held 75 from lengthwise displacement by its said disk

being between the near bearing 24a and an abutment 39 of the table). Parts 37 and 38 form the driving and driven members of a roller-clutch whose roller 40 is arranged against the inclined face 40a of a peripheral recess of the driven member 38 and is urged against the inner periphery of the driving member 37 by a spring-device 41. The bracket 21 affords a vertical guideway 21b for a slide or feeler 42 having its lower end forked and bent off (Fig. 8) toward the die, said feeler being pivoted to a lever 43 fulcrumed in said bracket and having pivoted thereto a depending forked dog 44 which straddles the clutch member. The system 42—43—44 tends in response to a spring 43a to assume a 15 position in which the lower forked end of the feeler enters notches 45 in the table. When a sheet is advanced it lifts the feeler and depresses the dog 44 into the path of the roller 40, thus disestablishing the clutch; when the sheet 20 passes beyond the feeler the system returns, the dog clearing the roller, thus reestablishing the clutch. In this way the rotation or non-rotation of the telescopic shaft respectively depends on the absence or presence of a sheet under the 25 feeler.

Referring, now, to housing 27 and the parts associated therewith (Figs. 5 and 7): In the housing is secured a bracket 46 (Fig. 7e) in which is guided at 46a the plunger 47a of a suction cup 47 arranged under the left fore-corner of the stack, the plunger having a lateral notch receiving a lever-plate 48 fulcrumed in a notch of the housing and normally urged upwardly by a spring 50 to bring the cup against the fore left 30 corner of the lowest sheet in the stack. (It is the arm 46b of bracket 46 which carries, as stated, abutment 23.) The lever-plate or lever is intermittently depressed by a cam 51 on the element 26 of the telescopic shaft to cause the suction cup to pull down said corner of the sheet. Affixed to the housing is a suction cylinder 52 the rod 53a of whose piston 53 terminates in a ring embracing an eccentric 54 on said element 26. This cylinder is connected, through a port 55 in the cylinder and a flexible tube 56, with the suction cup. At 57 (Figs. 5 and 7c) is a relief port for port 55, the same being normally closed by a valve 58a on a lever 58 fulcrumed at 59 and acted on by a spring 59a to hold the valve closed, 50 the lever being actuated to open port 57 by a cam 60 on element 26.

It will be seen that the plates *z*—*z'* lap each other and that plate *z'* terminates at the inner bearing 27a, (see Figs. 2, 3 and 7) thus leaving 55 the fore left corner of the sheet overhanging and thus adapted to be bent down as above stated; there may be a plate *z*² upon the left hand end of plate *z'* to support the left hand end of the stack at the proper level.

When the fore left corner of the sheet has been pulled down by the suction cup a gripper moves to the right to receive and grip and pull the lowest sheet *a'* back clear of separator 22a, thus incidentally breaking down any adhesion existing 65 between this and the next lowest sheet. This gripper (Fig. 7) comprises an actuated slide 61 movable under friction horizontally in a guideway 46c of the bracket 46 and affording the upper jaw of the gripper and a jaw 62 pivoted to the 70 slide and having an upstanding arm 62a. An actuating slide is formed by a plate 63 moving in a guideway 27x (Fig. 7b) of the housing 27 and two plates 64—65 secured to plate 63 and forming a notch 66 to receive the arm 62a of jaw 75

62. The plate 63 of this slide has an opening 67 to receive the upper end of a lever 68 fulcrumed at 69 in the housing and engaged with a barrel cam 70 on element 26 of the telescopic shaft. 5 When the actuating slide is moved by lever 68 to the right the action first is to move jaw 62 to open the gripper and then (the jaws impinging together at 61a Fig. 7f) move the gripper to the right to receive between its jaws the bent down corner of the sheet; when said slide now moves to the left jaw 62 is first closed to cause gripping of the sheet and then the gripper retracts to pull the sheet clear of separator 22a.

Assuming the left fore corner of the sheet has been thus pulled down by the suction cup and the sheet retracted by the gripper, a denter lever 71, fulcrumed at 27b in and at the back of housing 27 and arranged in line with the slot 9a so as to overlap the left-hand extremity of the sheet when retracted, is moved to dent said extremity of the sheet into the path of the extreme left-hand tooth 18a of rack 8. This lever is normally held retracted against a stop pin 72 by a spring 73; a cam 74 on element 26 of the telescopic shaft acts through a spring-pressed plunger 75 in the lever to effect the latter's denting movement. The denter lever acts to form an acute permanent downbend in the lowest sheet reaching into the path of said extreme left-hand tooth 30 and consequently of the other teeth of the rack, with the result that when the rack is reciprocating it slides the sheet along step by step, or intermittently.

The operation as so far described is as follows: 35 Assume shaft 7 to be driven and thereby reciprocating the rack and driving the clutch member 37; if the magazine is empty and there is no sheet under the feeler 42 the telescopic shaft will be driven and the mechanism shown in Figs. 5 and 7 will be actuated once for several thrusts of the plunger 4.

A stack of sheets is placed in the magazine. The fore-left corner of the lowest sheet will be pulled down by the suction cup clear of lug 23a 45 of the abutment 23, the gripper will advance, open, and receive the left end of the sheet and then, in its retracting movement, grip and pull the sheet to the left clear of separator 22a, and the denter lever will dent a portion of said end 50 into the path of the extreme left-hand tooth of the rack, which will then start the step-by-step advance past the die. (The relief port 57 is opened by lever 58 as soon as the gripper grips the sheet, so that the suction will not impede the advance of the sheet.) As soon as the leading or right-hand end of the sheet elevates the feeler 42 the system 42-43-44 will be set to dis-establish the clutch, so that the mechanism in Figs. 5 and 7 will cease operating, remaining so until the 60 sheet clears the feeler, when said mechanism will again go into action and repeat its said operations with respect to the next-succeeding sheet.

When a sheet has its left-hand end bent down 65 all possibility of the next succeeding sheet participating in the ensuing retraction of the first sheet is prevented by the depending lug 23a. The advance of the next-succeeding sheet to the right with the lowest sheet is prevented by abutment 70 22, and the separator 22a insures switching of the leading end of said lowest sheet away from the leading end of said next-succeeding sheet if there is possible adhesion between the sheets.

As for the sheet separating or parting constituting the initial step in the sheet-feeding: The

stack of superposed sheets is placed in the magazine with an edge portion of the lowest sheet (here at its forward right-hand corner) free to fall, at least with respect to said means, but held against falling by the separator or parting device 22a. The parting device projects toward the opposite edge of said lowest sheet. Hence, when the lowest sheet is retracted independently of the next superjacent sheet and in the direction in which the parting device projects and clear of the same and when said lowest sheet is then returned the parting by said device of the two mentioned sheets follows as an incident of said portion falling. If the terminus of said device has an underneath bevel, as shown, it will insure parting of the sheets should the falling of said portion be opposed by adhesion between the sheets.

It will be observed that the two principal functions of the means comprising parts 37, 38, 40 the telescopic shaft and the parts the latter actuates are (1) given a portion of the lowest sheet, as over the rack 8, free to be displaced downwardly, it acts to control the means as 71, which controls such displacement; and (2) given the ability of such sheet to be slid clear of a parting device, as 22a it acts to control the means, as the suction cup and grippers, which controls such shifting of the sheet. In the actual embodiment disclosed 37 constitutes a constantly moving driver; 38, the telescopic shaft and the parts actuated thereby constitute driven means; and roller 40 forms a clutch to clutch the driver with the driven means controlled from the advancing sheets through said system.

The housing 27, forming a support for the gripper, denter lever and suction cup, is secured to the table by bolts 16 (Figs. 2 and 7) passing through slots 71 in the latter extending lengthwise of the table whereby the housing may be adjusted to vary the distance between abutments 22 and 23, or the length of the magazine to suit various lengths of sheets.

Upon each sheet completing its passage past the die and punch it is ejected by the following mechanism (Figs. 1, 6, 8, 9 and 10 to 13):

The table terminates at the right in a housing 77 in which is journaled a transverse shaft 78 having fixed thereto a roller 79 whose periphery is about level with the table and having a bevel-pinion connection 80 with a shaft 81 journaled in and at the back and extending lengthwise of the table and having a pulley 82 engaging the belt 34, its contact therewith being assured by a pulley 83 journaled in a bracket 84 pivoted to an arm 85 of the table and subject to the pull of a spring 86. In a housing-like lever 87 fulcrumed on a shaft 88 connecting arms 89 of the housing 77 is journaled a roller 90 which is urged against the roller 79, with which it is parallel, by gravity and a spring 91 connecting lever 87 with the housing.

The lever 87 has a depending abutment 92 with which is coactive an abutment 93 on a rod 94, the abutments having coacting cam-faces. (Abutment 93 is equipped as a friction-clamp, as shown, 65 clamping the rod, which holds it in a given working position thereon while permitting it to be forcibly slid along the same to a different working position.) The rod is slideable in a stationary friction clamp 95 attached to the table and its left-hand end, in the lengthwise movement of the rod, always overhangs a ledge 2x of the bracket 14 so as to rest thereon at times, as will appear. Rack 8 has a forward tang 8x which overhangs rod 94 and in any event will engage, on the left-hand 70 75

stroke of the tang, an upstanding lug 94a of the rod. To the right of this lug the rod has a notch 94b to receive the tang, and forward of the notch the top surface of the rod is sufficiently low so that if the rod rests on the ledge the tang may reciprocate above and independently of the rod.

A lever 96 is fulcrumed in bracket 21 on a transverse horizontal axis and is equipped with a foot 97, projecting to the right, and is urged by a spring 98 to rest on the sheet being advanced. The left-hand arm of this lever or feeler has a roller 99 extending under the rod.

We have in the foregoing mechanism for feeding sheets or other lengths of stiff sheet material including a support (as the table) over which to advance said lengths, coacting grippers (as 79 and 87—90) to receive between them each length as it is advanced and one of which (87—90) is movable toward and from and normally urged toward the other and one of which includes a constantly rotating length-ejecting member (79), means to advance said lengths in succession and step-by-step including a constantly reciprocating element (the rack 8), a shifter element (93—94) to move the movable gripper from the other gripper reciprocatorily with the reciprocating element and also movable transversely of the path of said reciprocating element into and out of and normally urged (here by gravity) out of coupled relation therewith, said elements having coacting portions (as 94a and the left side of tang 8x) to shift the shifter element to that limit of motion with the reciprocating element, in either the coupled or uncoupled relation of said elements, in which the shifter element has moved the movable gripper from the other gripper, and a feeler (96) normally urging the shifter element into position to be coupled with the reciprocating element and movable by the advancing lengths to release the same. That is to say:

Assume a sheet is being advanced by the rack step by step and is between the grippers, which are open because while the feeler has been moved by the sheet and allowed the shifter to fall into uncoupled relation to the rack, the coaction of the mentioned portions has resulted in the rack shifting the shifter to the left, elevating the movable gripper (the positions of the parts in their here mentioned relation being shown by dotted lines in Fig. 13). The sheet, in being advanced, finally allows the feeler to assume its normal (or full-line) position, whereby the shifter becomes coupled with the rack and, moved thereby to the right, (full-line position) allows the movable gripper to fall, with consequent ejection of the sheet by constantly rotating element 79.

Having thus fully described our invention what we claim is:

1. In combination, means to support a stack of superposed sheets with the opposing surfaces of the lowest sheet and the next lowest sheet in face to face contact and an edge portion of said lowest sheet free of said means to fall, a sheet-parting device projecting under such edge portion toward the opposite edge of said sheet and opposing falling of said edge portion, and means to move such sheet in said plane clear of said device and independently of the next superjacent sheet, whereupon on movement of the lowest sheet oppositely to its first movement said device will part such sheet from the next superjacent sheet.

2. In combination, means to support a stack of superposed sheets with the lowest sheet therein in a given plane and an edge portion of said lowest sheet free of said means to fall, a sheet-parting

device projecting under such edge portion toward the opposite edge of said sheet and opposing falling of said edge portion and having an underneath bevelled terminus, and means to move such sheet in said plane clear of said device and independently of the next superjacent sheet, whereupon on movement of the lowest sheet oppositely to its first movement said device will part such sheet from the next superjacent sheet.

3. In a mechanism for operating on a stack of sheets having a generally angular contour in plan, the combination of supporting structure including a table on which the stack is adapted to rest with one side inclusive of a corner of the stack projecting further than the table, means to advance the lowest sheet independently of the other sheets in the stack in the direction in which said side projects, said structure also including a support supporting the projecting portion of the stack and arranged to be remote from said corner when the stack is so positioned, and an abutment opposed to said side of the stack and having a depending stop relatively between said support and said corner of the stack and terminating below the top surface of said lowest sheet, whereby the portion of the lowest sheet inclusive of said corner must be bent downward below the stop when the sheet is to be advanced by said means.

4. In a mechanism for operating on a stack of sheets, the combination of supporting structure on which the stack is adapted to rest, means to slide the lowest sheet in one direction independently of the others in the stack, and means thereupon to slide said sheet independently of the others in approximately the opposite direction, said structure having means to oppose displacement of the next lowest sheet with the lowest sheet when the latter is slid in either direction.

5. In a mechanism for operating on a stack of sheets, the combination of supporting structure on which the stack is adapted to rest, means, movable in a path below the stack, to slide the lowest sheet in one direction independently of the others in the stack, means to slide said sheet independently of the others in approximately the opposite direction and means to bend a portion thereof down into said path, said structure having means to oppose displacement of the next lowest sheet with the lowest sheet when the latter is slid in either direction.

6. In combination, means to support a stack of sheets and oppose movement of the next-lowest sheet in the stack in one direction, means, movable in said direction under the stack, to slide the lowest sheet in the stack in said direction and means to form an acute permanent downbend in said lowest sheet reaching into the path of movement of the second-named means.

7. In combination, supporting structure for a stack of sheets opposing sliding movement of the next lowest sheet in the stack, a rack structure, movable in said direction and back repeatedly under the stack, to slide the lowest sheet in the stack over the first structure, and means to form an acute permanent downbend in said lowest sheet reaching into the path of movement of the rack structure.

8. In combination, supporting means including a table on which to support a stack of superposed sheets, a reciprocatory element arranged to move in a path parallel with and under the lowest sheet in the stack and having an upwardly projecting tooth below the plane of such sheet, means, offset from the stack lengthwise of said path but within the range of movement of the

tooth, to bend a portion of such sheet which traverses said path into the path of said tooth, and means to shift said sheet toward and into the control of the bending means.

5 9. In combination, supporting means including a table on which to support a stack of superposed sheets, an abutment for one side of the stack above and spaced from the table, means, below and spaced from the stack, to advance the lowest 10 sheet in the stack under the abutment, a support adjustable on the table toward and from the abutment, and means on the support to force a part of the lowest sheet into the control of the advancing means.

15 10. In combination, supporting means including a table on which to support a stack of superposed sheets, an abutment for one side of the stack above and spaced from the table and having a sheet-parting device projecting therefrom under the stack and on which the portion of the stack near the abutment rests, a support adjustable on the table toward and from the abutment, means on the support to shift the lowest sheet in the stack from the abutment clear of 20 said device, and means thereupon to advance the sheet under the abutment.

25 11. In combination, means to support a stack of superposed sheets with a portion of the lowest sheet in the stack free to be displaced downwardly, means, below the stack in position to engage the portion of the lowest sheet so displaced, to slide such sheet over the supporting means, means for defining such displacement of such portion, and means, controlled from the advancing sheets, to control the last-named means.

30 12. In combination, supporting means for a stack of superposed sheets, means to slide the sheets one after another from the bottom of the stack, means for forcing a part of the lowest sheet in the stack into the control of the advancing means, and means, controlled from the advancing sheets, for controlling the last-named means.

35 13. In combination, supporting means including a table on which to support a stack of superposed sheets, an abutment for one side of the stack above and spaced from the table and having a sheet-parting device projecting therefrom under the stack and on which the portion of the stack near the abutment rests, means to advance the sheets one after another from the bottom of the stack under the abutment, means to slide the lowest sheet in the stack from the abutment, means to slide the lowest sheet in the stack from the abutment and clear of said device prior to advance of such sheet, and means, controlled from the advancing sheets, for controlling the last-named means.

40 14. In combination, means to support a stack of superposed sheets with a portion of the lowest sheet in the stack free to be displaced downwardly means, below the stack in position to engage the portion of the lowest sheet so displaced, to slide such sheet over the supporting means, a constantly moving driver, driven means for defining the displacement of said portion, means to clutch the driven means with the driver for movement therewith, and means, controlled by the sheet being advanced, for controlling the clutching means.

45 15. In combination, supporting means for a stack of superposed sheets, means to slide the sheets one after another from the bottom of the stack, a constantly moving driver, driven means

including an instrumentality for forcing a part of each lowest sheet in the stack into the control of the advancing means, means to clutch the driven means with the driver for movement therewith, and means, controlled by the advancing sheets, for controlling the clutching means.

50 16. In combination, supporting structure including a table on which to support a stack of sheets and a parting device to project under the stack at one side thereof and hold said side elevated above the table, the lowest sheet being slidably independently of the others in the stack clear of said device, means to control such sliding of said lowest sheet, means, upon said lowest sheet sliding clear of said device, to advance such sheet under said device, and means, controlled from the advancing sheet, to control the first-named means.

55 17. In combination, supporting means including a table on which to support a stack of superposed sheets, an abutment for one side of the stack above and spaced from the table and having a sheet-parting device projecting therefrom under the stack and on which the portion of the stack near the abutment rests, means to advance the sheets one after another from the bottom of the stack under the abutment, a constantly moving driver, driven means including an instrumentality for sliding the lowest sheet in the stack from the abutment and clear of said device prior to advance of such sheet, means to clutch the driven means with the driver for movement therewith, and means, controlled by the advancing sheets, for controlling the clutching means.

60 18. Mechanism for feeding lengths of stiff material including a support over which to advance said lengths, coacting grippers arranged to receive between them each length as it is advanced and one of which is movable toward and from the other and one of which includes a constantly rotating length-ejecting member, means to advance said lengths in succession including a constantly reciprocating member, a feeler movable by the advancing lengths, and means, controlled by the feeler, for coupling the movable gripper with the latter member.

65 19. Mechanism for feeding lengths of stiff material including a support over which to advance said lengths, coacting grippers arranged to receive between them each length as it is advanced and one of which is movable toward and from and normally urged toward the other and one of which includes a constantly rotating length-ejecting member, means to advance said lengths in succession and step by step including a constantly reciprocating element, a shifter element to move the movable gripper from the other gripper reciprocatorily with the reciprocating element and also movable transversely of the path of said reciprocating element into and out of and normally urged out of coupled relation therewith, said elements having coacting portions to shift the shifter to that limit of motion with the reciprocating element, in either the coupled or uncoupled relation of said elements, in which the shifter element has moved the movable gripper from the other gripper, and a feeler normally urging the shifter element into position to be coupled with the reciprocating element and movable by the advancing lengths to release the same.
